AUTOMATIC MECHANICAL BLOCK RAILROAD SIGNAL.

No. 481,884.

Patented Aug. 30, 1892.

UNITED STATES PATENT OFFICE.

GEORGE CURSON YOUNG AND GEORGE O. WILLEVER, OF PHILLIPSBURG, NEW JERSEY, ASSIGNEES OF ONE-THIRD TO JOHN M. R. SHIMER, OF SAME PLACE.

AUTOMATIC MECHANICAL BLOCK RAILROAD-SIGNAL.

SPECIFICATION forming part of Letters Patent No. 481,884, dated August 30, 1892.

Application filed December 5, 1891. Serial No. 414,143. (No model.)

To all whom it may concern:

Be it known that we, GEORGE CURSON YOUNG and GEORGE O. WILLEVER, citizens of the United States, residing in Phillipsburg, in the county of Warren and State of New Jersey, have invented certain new and useful Improvements in Automatic Mechanical Block Railroad-Signals, of which the following is a specification.

10 Our invention relates to a block-signal system for railroads and other purposes; and it has for its object to provide means which shall be mechanically operated by a passing train and which shall clearly indicate the entrance 15 of a train upon a certain portion or block of the railroad and shall also indicate when such block is clear, as when the entire train has passed beyond said portion or block.

To these ends our invention consists in the 20 features of construction, arrangement, and mode of operation, substantially such as are hereinafter more particularly pointed out.

Referring to the accompanying drawings, wherein we have illustrated the general principles of our invention, Figure 1 is a side view representing a portion of a railroad embracing three signal-posts, including two blocks. Fig. 2 is a plan view of the same. Fig. 3 is a vertical transverse section on the 30 line 33, Fig. 2; and Fig. 4 is a side view of the compensator.

In the large and increasing business done on railroads it has become necessary to provide some means by the aid of which the engineer 35 of a train or other person can readily determine the condition of the track ahead of him in regard to other trains, and various means have been suggested whereby this can be accomplished. It has been common to divide 40 the railway track or way into a series of sections, ordinarily known as "blocks," and to provide signal devices which shall indicate to an approaching train whether the preceding block or blocks are clear—that is, whether the 45 preceding train has passed beyond said block. It has been proposed to operate these signal devices by the aid of electricity for various purposes; but owing to the well-known uncertainties of operation of electrical appliances their practical use to any great extent is

objected to, and efforts have been made to provide mechanical devices which shall be operated, preferably, automatically by a passing train and which shall indicate exactly the condition of the preceding and succeeding 55 block or blocks of the approaching train.

Our invention has for its object, primarily, to provide means whereby this may be accomplished, so that whether the preceding block or blocks are perfectly clear or not will 60 be determined with safety; and a further object of our invention is to provide means for accomplishing this result which shall be exceedingly cheap, simple, and effective, being positive in their movements and capable of 65 being automatically operated by the passing train.

With this general statement in regard to our invention we will now proceed to describe its embodiment, as illustrated in the accompanying drawings, so that those skilled in the art will be enabled to apply and use the principles of our invention.

In the drawings, A A' represent the rails of an ordinary track, and arranged at suitable 75 distances along said track, and preferably at one side thereof, are the signal-posts B B' B'', &c., which posts represent the terminals of the respective sections or blocks of the track. Mounted on these signal-posts are some proper 80 signal devices, and we have represented ordinary semaphores C C' C'', although it is evident that other specific signal devices may be used. These may be provided with suitable lamps or other means for signaling in the 85 night-time; but for the sake of clearness we have simply shown the semaphores as pivotally mounted on their respective signal-posts and as being connected by rods or bars D D' D'' to suitable levers E E' E''. These levers 90 are preferably weighted, as indicated, so that when they are free to move the semaphores will be automatically set to "danger," so that in case of accident or failure to operate on the part of the signal devices the section of the 95 road will be "blocked" automatically until the fault is found and remedied. In order to operate these semaphores, we connect these levers E by means, for instance, of a rod or rods F with cross-levers G G' G'', &c., and these 100

levers are pivotally mounted in suitable supports H^3 , arranged adjacent to one of the rails of the track, and are so arranged that the long arms of the lever shall be connected to the 5 semaphore-levers, while the short arms shall be arranged to be operated upon automatically by some suitable device intermediate of said ends and the passing train. In order to provide means for operating these levers, it 10 is desirable that some arrangement should be made which can be readily applied to existing roads without requiring any specific form or construction of rails and which shall interfere in the least possible manner with the 15 strength of the rails. In order to accomplish these results, we provide rail-levers H H' H^2 , &c., which are shown as plates having a curved upper surface h and as being pivoted to the rail, as at h' , while the free ends are provided 20 with tongues or projections h^2 , which are arranged to bear upon the levers G G' , &c. These rail-levers are made of a considerable length, so that when they are in a position to be struck by the locomotive or other portion of 25 the train and to operate the semaphore they will present a gradually-inclined raised portion, over which the train will pass and by means of which the semaphores and their connections will be operated with a comparatively 30 slow but continuous movement until they are properly set. By this means we avoid the danger of breaking or injuring the semaphores by too sudden impact upon the operating mechanism by a swiftly-moving train. When 35 the levers are in their depressed condition, their lower edges will lie parallel to and practically upon the upper edge of one of the flanges a of the rails A , while the tongue or projection h^2 of the levers will extend through 40 cut-away portions of the flanges and will bear upon the signal-operating levers. In this way it will be seen that it is only necessary to remove a slight portion of one of the flanges of a rail in any existing track and to perforate 45 the web thereof for the reception of the pivot-pin h' , in order to apply our invention thereto. In applying these rail-levers we preferably make use of filling-pieces A^2 , which fit into the sides of the rails between the flange and 50 tread, thereby providing an even smooth surface, against which the rail-levers bear.

In order that a semaphore at the block-station in advance or in the rear of the train may be suitably operated by the rail-lever at 55 that point, we connect the semaphores between the signal-posts by means of a chain, wire, rod, or similar device J , the ends of these rods being flexible and adapted to pass over the guide-pulleys K , which may be mounted 60 upon the signal-posts. As the distance between two signal-posts in some instances is quite large, in order that any slack or stretch of these rods or ropes may be taken up we provide suitable compensators L , which may 65 be of any suitable construction, the preferred form being illustrated more particularly in Figs. 2 and 4, in which there is a weighted

lever l , provided with a friction-roll l' , arranged to bear on the under portion of the wire or connection J , which at this point is 70 passed under the bearing pulleys or wheels J' . It will readily be seen that the weighted lever will operate to take up any slack in the connection J and avoid any lost motion therein, so that the semaphore at one station may 75 be readily and positively operated by a lever at another station.

If it were only necessary to set the semaphore or signal to "danger" as the train enters a block, only a single rail-lever would be 80 necessary. Thus at the station or block 1, which is represented as the beginning of the block system, we have provided only a single-rail-lever H , as it is only necessary that the train in passing shall insure that the corresponding semaphore C shall be set at "danger." When, however, it is desired that this signal shall be set at "safety" when the train has passed out of the block guarded thereby, it is necessary to provide other means 85 located at the station 2, which shall operate the signal at station 1 and set it to "safety." To do this, we provide at all the intermediate stations two rail-levers, as $H' I$ and $H^2 I'$, and these latter rail-levers I I' are preferably 90 placed outside of the first series of rail-levers H H^2 , and while they may be mounted upon the same pivot they are preferably made longer and are arranged to bear upon the levers M M' , which are shown as mounted so 95 as to operate at the other side of the posts B B^2 from the levers G G^2 , and are preferably provided with weighted levers N N' , to which the connections J are secured. The rail-levers H are arranged in such relation to the tread 100 of the rails that the ordinary flanged wheel of the locomotive as it approaches the station will depress these levers in a gradual manner and leave or set the semaphore to "danger," and by suitable connections (indicated by the 105 dotted lines O) it can be arranged so that the semaphore at the next preceding station shall be set at "danger." While this is an advantage in some instances, as in single-track lines, as a rule we prefer not to operate the 110 preceding semaphore corresponding to the block into which the train is passing.

It is well known that oftentimes a train becomes parted, so that while the engine passes on beyond a block one or more of the 115 cars remain, and of course is a source of danger to a succeeding train; and it is one of the essential objects of our invention to so arrange the parts that the semaphore shall not be set at "safety" at any block until the 120 whole of the train has passed out of said block and it is entirely free for the next coming train. To accomplish this, we arrange the safety-setting rail-levers I at a sufficient distance from the tread of the rail to prevent 125 their being operated by the ordinary flanged wheel of the engine or cars, and we provide a broad-tread wheel in the case of a freight-train or coal-train where it is usual to have 130

what is known as a "caboose" or "guard-car" at the rear thereof, and this broad-tread wheel of the caboose will operate to set the signal to "safety," and not until the caboose 5 has passed out of the block will this operation take place. Such broad-tread wheels can take the place of two of the ordinary wheels of the caboose, one being arranged on each side, so that one or the other will operate the 10 signals regardless of the direction in which the caboose is moving. In passenger-trains, on the contrary, the cars are coupled together indiscriminately, so that it is necessary to provide the cars with some sort of a mechanism 15 which can be readily adapted to operate the devices to set them at "safety" as the last car of the train passes out of the block, and while various appliances may be used we have shown an arm P, which is permanently attached 20 to the frame of the truck T and which is properly braced thereto, and at its free end has a pin p, adapted to receive and hold a wheel Q, which is preferably of about one-half the diameter of the ordinary wheel. As one of 25 these arms P is secured upon each side of each car, it can be readily seen that by simply attaching the wheel to the proper arm of the last car of a train the signals will only be set to "safety" when said wheel passes over the 30 corresponding rail-lever I and the block is entirely free for the passage of the incoming train.

Such being the general construction and arrangement of our invention, its operation 35 will be understood from the drawings and may briefly be stated as follows: In the normal condition of the line all the semaphores are set at "safety" and all the rail-levers H H', &c., project normally above the treads of 40 the rail, and as soon as the engine approaches the block the rail-lever H is gradually depressed and the corresponding semaphore C is set to "danger," and the train passes through the block until it reaches the next 45 signal-post B', where the wheel passing over the rail-lever H' sets the semaphore C to "danger;" or in the modification suggested it may in some instances set the next succeeding semaphore to "danger" also, and the 50 first semaphore still remains at "danger." If, for instance, the train has passed and the caboose of a freight-train or the last car of a passenger-train still remains on the block between the signal-posts B and B', the semaphore 55 C at the first station would continue to show "danger;" but if the train has passed properly, the broad wheel W on the caboose or the small wheel Q on the rear passenger-car will come in contact with the track-lever I at 60 station B' and these will operate through the medium of the lever M and the connection J to positively restore the semaphore C to safety position, and the engine of a train approaching this signal-post will know that the block 65 ahead is free, the whole of the preceding train having passed out of it. This operation will continue throughout the system of blocks, it

being understood that the first wheel of the locomotive will set one or more of the semaphores to "danger," while the last wheel of the 70 train will restore the preceding semaphore to a position of safety as it passes a given signal, and unless the rear portion of the train safely passes the preceding station will show "danger" 75

It will be observed that all the operations, both in setting the semaphores to "danger" and to "safety," are positive in their action, and that the operative parts of the signal are exceedingly simple in construction, cheap of 80 manufacture, and can readily be applied to roads already in existence, so that the initial cost of introducing the system is comparatively small.

It is evident that, instead of the semaphore 85 or in connection with the semaphores shown herein, we may use other signal devices—as, for instance, an audible-signal device in the shape of a gong—but as these signals form no part of our present invention they need not 90 be particularly described, it being evident that they may be used to meet the desires of any particular conditions—as, for instance, an audible signal may be used in case of fog or other interference with the ready sight of 95 the semaphores.

What we claim is—

1. The combination, with a series of signals arranged along the track, of two series of rail-levers pivotally mounted on the rails, one series being arranged within the tread of the ordinary wheel to be operated by the engine and the other series being arranged beyond the tread of the ordinary wheel to be operated by the passage of the rear car of the 100 train, substantially as described.

2. The combination, with a series of signals arranged along the track, of two series of rail-levers pivoted to the rails, one series being arranged within the tread of an ordinary 105 wheel to be operated by the engine to set the adjacent section to "danger" and the other series of levers being arranged without the tread of the ordinary wheel and connected to the signal at the beginning of the block 110 through which the train has passed to operate the signal to "safety" as the rear car of the train moves over said levers, substantially 115 as described.

3. The combination, with the rail, of two series of rail-levers mounted on the same pivot and connected directly to the side of the rail and each having curved portions projecting above the tread of the rail and a tongue or projection extending below the flange of the 120 rails, one of the levers of each pair being longer than the other, substantially as described.

4. The combination, with the rail, of two series of rail-levers pivotally attached directly 125 to the rail, but at different distances therefrom, a series of signal-posts arranged along the track, connections between the inner rail-lever and the signal upon the post adjacent 130

to said lever, and connections between the signal on the next preceding post and the outer lever, substantially as described.

5. The combination, with a series of signal-posts arranged along the track, of two series of rail-levers pivotally connected to the track, one series being within the tread of an ordinary wheel and the other series beyond the tread, connections between the inner lever and the signal on the adjacent post, and connections between the outer lever and the signal of the next preceding post, the respective connections being on opposite sides of the post adjacent to the levers, substantially as described.

6. The combination, with a series of signal-posts arranged along the track, of two series of rail-levers pivotally connected directly to the rail, a lever G, connected to the signal adjacent to the track and arranged to be operated by the inner track-lever, and a lever M, arranged to be operated by the outer track-lever and connected to the signal on the next preceding post, the arrangement being such that the inner rail-lever will be operated by the passing of an ordinary wheel, while the outer lever will be operated only upon the passing of a special wheel projecting beyond the tread of the ordinary wheel, substantially as described.

7. The combination, with the rail, of a track-lever pivotally mounted on said rail, a filling-piece between said lever and the web of the

35 rail, the lever being within the tread of an ordinary wheel, and another track-lever mounted upon the same pivot and arranged outside the tread of an ordinary wheel and adapted to be operated by a wheel having an extended tread, substantially as described.

8. The combination, with the signal-posts 40 carrying semaphores arranged along the track, of the track-levers H and I, pivotally connected to the rail, one of the levers being longer than the other and outside the tread of the ordinary wheel, the levers G and M respectively operated by the track-levers, connections between the lever G and the semaphore C adjacent to the track-levers, and flexible connections between the lever M and the next preceding semaphore, and a take-up 45 device for said flexible connections, substantially as described.

In testimony whereof we have signed our names to this specification in the presence of the subscribing witnesses.
